ELECTRIC SOCKET

Van L. Vendope, Fort Worth, Tex., assignor to
Economy Electric Ad Corporation, Fort Worth,
Tex., a corporation of Texas

Application April 10, 1934, Serial No. 719,822

6 Claims. (Cl. 173—339)

This invention relates to new and useful improvements in electric sockets.

One object of the invention is to provide an improved flexible socket so arranged that it may be slipped or pushed onto the threaded terminal of an ordinary electric lamp without screwing or rotating either the lamp or the socket, whereby a quick connection may be made and contact assured; also whereby a less expensive socket and 10 more simple socket may be produced.

A further object of the invention is to provide an elastic socket in which the contacts may be mounted without vulcanizing them therein.

Another object of the invention is to provide an 15 elastic socket having its end or cap arranged to be extended when the socket is pushed onto the terminal of a lamp.

Still another object of the invention is to provide an elastic socket for connection to the terminal of a neon tube so arranged as to prevent 20 electrical interference, common to high voltage.

An important object of the invention is to provide a flexible socket made in the form of a cap, whereby the terminal of a lamp may be mounted 25 in a support and the socket slipped on the projection of said terminal.

A construction designed to carry out the invention will be hereinafter described, together with other features of the invention.

30 The invention will be more readily understood from a reading of the following specification and by reference to the accompanying drawing, in which an example of the invention is shown, and wherein:

35 Figure 1 is a view showing a pair of electric lamps having their terminals screwed through a support and sockets constructed in accordance with the invention pushed onto said terminals, one of said sockets being shown in elevation and 40 the other socket being shown in section.

Figure 2 is a sectional view of another form of 45 socket before being engaged with a lamp or other terminal.

Figure 3 is a view similar to Figure 1 and showing 50 sockets like Figure 2 engaged on the lamp terminals.

Figure 4 is a perspective view of another form of socket, and

55 Figure 5 is a sectional view of a socket for neon tube terminal.

This application is filed as a continuation in part of my co-pending application filed Oct. 14th, 1932, Serial No. 637,675, which latter application was filed as a continuation in part of an original 55 application filed Dec. 17, 1931 Serial No. 581,642

which has matured in Patent No. 1,914,161, issued June 13, 1933, both of which were filed in my former name Veno L. Pistocco.

In the drawing the numeral 10 designates the shell or body of a socket. This shell is preferably 5 made in the form of a thimble and is provided with an outwardly directed annular rim or lip 11, as is shown in Figure 1. The shell in this form is made of some flexible or yieldable material, such as rubber composition, or any other material suitable for the purpose. It is also preferable to form the shell of electrical non-conducting material. In the bottom of the socket I mount a metallic contact 12 connected with a wire 13. A second metallic contact 14 is mounted within the 15 shell and against the side thereof, so as to be spaced from the contact 12 and insulated therefrom. A wire 15 leads from the contact 14.

In Figure 1 I have shown ordinary electric lamps A screwed through a vertical support B, so 20 that their screw-threaded terminals C are exposed on the rear side of the support. In order to electrically connect these lamps, it is merely necessary to push or slip the flexible shells 10 onto the terminals C. In each socket the contact 14 engages with the terminal C and the contact 12 engages with the end terminal D. The flexible nature of the shell causes it to remain in frictional contact with the lamp terminal, whereby it is held in place. The rim 11 engages against 25 the rear side of the support B and thus forms a seal so that the terminal of the lamp is completely covered. The socket may be quickly slipped onto the terminal and as readily removed therefrom. This form of socket may be attached 30 to lamps which are mounted in a support as shown in Figure 1, or the sockets may be suspended by the wires 13 and 15 and lamps slipped 35 thereinto.

In Figures 2 and 3 I have shown another form 40 of socket having the same general features as are set forth in Figure 1. The socket 20 is preferably made of some elastic or extensible material, such as rubber compound. In Figure 2 the socket 20 is shown before it is applied to a terminal, while 45 in Figure 3 the socket is shown applied to a lamp terminal and extended. This socket has comparatively thick side walls and the rim 11 is eliminated. A reduced annular portion 21 is provided at the bottom of the socket surrounding a boss 22. 50

When the socket is placed on the lamp terminal C the reduced portion 21 permits the bottom and the boss 22 to be extended, whereby the socket is tensioned and more positive contact provided at the end of the lamp terminal, sufficient frictional 55

engagement is maintained between sides of the socket and the threads of the terminal, that the edge of the socket may be engaged with and held against the surface of the support B. As in 5 Figure 1 the projecting portion of the terminal C is completely covered.

In the boss 22 is mounted a double flanged contact 23; while in the side wall of the socket, a double flanged contact 24 is mounted. By forming 10 the socket with holes to fit the shanks of the contacts, the flanges or heads of the latter may be pushed through said holes, and the contacts thus mounted in the socket, without vulcanizing them therein. The engagement of the lamp terminal contact D with the contact 23 is made more positive by the extension of the socket. If it is desired to make the socket more flexible, one or 15 more grooves 25 may be made in the side wall as is shown in Figure 4.

20 This form of socket lends itself nicely to connections for neon tubes as is shown in Figure 5. In order to grasp the glass tube E inwardly of the terminal cap of the electrode the socket 20 is provided with an inwardly directed lip 26, 25 otherwise the socket is substantially the same as in Figures 2 and 3. However to guard against interfering electrical influences the inner surface of the socket may be glazed and a shroud or jacket 27 slipped over the socket, electrode and 30 wires. The shroud is formed of thin layers or nested sleeves of different colors and qualities. The inner ends of these sleeves are stepped so that each will contact the glass tube E. As an illustration the inner jacket a may be of a hard 35 cured rubber having a highly glazed surface, while the next sleeve b may be of soft cured rubber of a contrasting color. The next outer contacting sleeve c may be similar to sleeve a, but of a contrasting color to sleeve b; while sleeve d 40 may be like sleeve b. These elements are subject to considerable variation according to the electrical frequency and voltage.

The sockets which have been described may be characterized as "push-on" sockets, because 45 they may be quickly and easily pushed on the lamp or other terminals. The wires 13 and 15 may be soldered to the heads or flanges of the contacts 12, 14, 23 and 24 or otherwise secured thereto. However soldering assures a good connection and enables a number of sockets to be 50 connected in a string to the wires. It will be seen that a string of sockets may be easily and quickly pushed in the projecting terminals C as in Figures 1 and 3. This makes for economy and 55 simplicity.

In making up an illuminated sign the letters are painted in beaver board or other support as B. Holes are bored through the lettered portions of the support (Figure 3) and the lamp terminals screwed through said holes. The sign is quickly completed by pushing the sockets 10 or 60 20 onto the lamp terminals. The sign is quickly and easily made and at a low cost. The sockets may be easily removed and used many times 65 without injury. This socket tends itself to a general use for both indoor and outdoor purposes. No tools are required and owing to the intimate contact between the sockets and the support B the terminals are sealed and properly insulated. By making the socket so as to 70 push on the terminal, screw threaded nipples and the like are not required in the bore. The bore is made smooth and the contacts are separated, thus the socket is held on the terminal solely 75 by the frictional contact between its smooth bore

and the terminal. It is obvious that if screw threads were employed the lamps would have to be screwed into the sockets as the latter being fastened to the wires could not be rotated without badly twisting the wires. This operation would be slow and impractical because either two workmen would be required or it would be difficult to hold the socket in one hand and reach the lamp with the other hand, particularly where the lamp was in the middle of a sign five feet 10 high.

The description which has been given recites more or less detail of a particular embodiment of the invention, which is set forth as new and useful; however, I desire it understood that the invention is not limited to such exact details of construction, because it is manifest that changes and modifications may be made, within the scope of the appended claims, without departing from the spirit of the invention.

20 What I claim and desire to secure by Letters Patent, is:

1. The combination with a support having holes therein and electric lamps having their bases inserted through the holes of said support and projecting from the rear side of said support, of a plurality of flexible sockets having spaced metallic terminals exposed therein and connected to a pair of electric circuit wires, said sockets being constructed to be pushed onto said projecting lamp bases so as to intimately engage the rear side of said support and completely cover the projecting lamp bases and also whereby the terminals engage said lamp bases.

2. The combination with a support having holes therein and electric lamps having their bases inserted through the holes of said support and projecting from the rear side of said support, of a plurality of rubber sockets having spaced metallic terminals exposed therein and connected to a pair of electric circuit wires, said sockets being constructed to be pushed onto said projecting lamp bases so as to intimately engage the rear side of said support and completely cover the projecting lamp bases and also whereby the terminals engage said lamp bases.

3. A detachable socket adapted to be pushed onto and pulled off the base of an electrical lamp including, a flexible non-metallic body having a recess therein for receiving a lamp base when said body is pushed onto said lamp base, a metallic terminal mounted in the closed end of the recess of the body and exposed therein for contact with the end of a lamp base, and a second metallic terminal of such size and so located in the side 55 of the recess of the body as to contact with side of a lamp base when the body is pushed on such a base, the recess of the body being less in depth than the length of a lamp base, whereby said body may be grasped with one hand and quickly pushed 60 on a lamp base and the terminals engaged with such a base or quickly pulled from such a base.

4. A plurality of sockets adapted to be pushed onto and pulled off the bases of electric lamps, each socket including a flexible non-metallic body 65 having a recess therein for receiving a lamp base when said body is pushed onto said lamp base, a metallic terminal mounted in the closed end of the recess of the body and exposed therein for contact with the end of a lamp base, and a second 70 metallic terminal of such size and so located in the side of the recess of the body as to contact with side of a lamp base when the body is pushed on such a base, the terminals of each socket being connected with the terminals of the other sockets 75

by electric circuit wires, the recess of each body being less in depth than the length of a lamp base, whereby said sockets may be grasped and quickly pushed on the lamp bases and the terminals engaged with the bases.

5. A detachable socket adapted to be pushed onto and pulled off the base of an electrical lamp including, a flexible non-metallic body having a recess therein for receiving a lamp base when said body is pushed onto said lamp base, a metallic terminal mounted in the closed end of the recess of the body and exposed therein for contact with the end of a lamp base, and a second metallic terminal of such size and so located in the side of the recess of the body as to contact with side of a lamp base when the body is pushed on such a base, the recess of the body being less in depth than the length of a lamp base, whereby said body may be grasped with one hand and quickly pushed on a lamp base and the terminals engaged with such a base or quickly pulled from such a base, the wall at the closed end of the recess of

the body having a portion reduced in thickness, whereby the end wall of said recess may be extended to assure contact with the terminal thereof at when the socket pushed on a lamp base.

6. A detachable socket adapted to be pushed onto and pulled off the base of an electrical lamp including, a flexible non-metallic body having a recess therein for receiving a lamp base when said body is pushed onto said lamp base, a metallic terminal mounted in the closed end of the recess of the body and exposed therein for contact with the end of a lamp base, and a second metallic terminal of such size and so located in the side of the recess of the body as to contact with side of a lamp base when the body is pushed on such a base, the body being short and its walls sufficiently thick to permit it to be grasped with one hand and quickly pushed on or pulled from a lamp base, the terminals being so located in the recess of the body as to assure contact with a lamp base.
